(57) **CLAIM**

The ornamental design for a “combination flowmeter and regulator module”, as shown and described.

DESCRIPTION

FIG. 1 is a perspective view of a first embodiment of a combination gauge and meter, showing my new design;

FIG. 2 is a front elevational view thereof;

FIG. 3 is a left side elevation view thereof;

FIG. 4 is a rear elevational view thereof;

FIG. 5 is a right side elevational view thereof;

FIG. 6 is a top plan view thereof; and

FIG. 7 is a bottom plan view thereof;

FIG. 8 is a perspective view of a second embodiment of a combination gauge and meter, showing my new design as mounted onto a gas bottle;

FIG. 9 is a front elevational view thereof;

FIG. 10 is a left side elevation view thereof;

FIG. 11 is a rear elevational view thereof;

FIG. 12 is a right side elevational view thereof;

FIG. 13 is a top plan view thereof; and,

FIG. 14 is a bottom plan view thereof.
